The ornamental design for a soft food feeder, as shown and described.

DESCRIPTION

FIG. 1 is an upper left perspective view of a soft food feeder showing a first embodiment of our new design;
FIG. 2 is an exploded upper perspective view thereof;
FIG. 3 is a bottom left perspective view thereof;
FIG. 4 is a bottom right perspective view thereof;
FIG. 5 is a front view thereof;
FIG. 6 is a back view thereof;
FIG. 7 is a left side view thereof;
FIG. 8 is a right side view thereof;
FIG. 9 is a top view thereof; and,
FIG. 10 is a bottom view thereof.

The broken lines shown in the drawings represent environmental structure in FIGS. 1–8 and 10 that form no part of the claimed design.
